UNITED STATES PATENT OFFICE.

ROBERT M. COLE, OF SANDUSKY, OHIO, ASSIGNOR OF ONE-HALF TO PAUL O. COLLINS,
OF SANDUSKY, OHIO.

SUBLIMATING APPARATUS.

Application filed November 7, 1921. Serial No. 513,847.

To all whom it may concern:

Be it known that I, ROBERT M. COLE, a citizen of the United States of America, and a resident of Sandusky, county of Erie, and State of Ohio, have invented a new and useful Improvement in Sublimating Apparatus, of which the following is a specification.

The main objects of this invention are to provide an improved form of apparatus for use in obtaining certain chemical substances by a process of sublimation; to provide an improved apparatus for this purpose wherein the crude material is fed into the apparatus continuously and the vapors and the waste products are likewise extracted from the apparatus simultaneously; to provide an improved construction and arrangement of the vaporizing mechanism; to provide improved means for delivering the crude material and admitting it to the vaporizing mechanism; to provide improved means for extracting the waste material from the vaporizing mechanism; to provide an improved construction and arrangement of the chamber wherein the vapors are solidified; to provide improved means for adjusting the apparatus so as to regulate the velocity of the flow of the fluid substance through the vaporizing mechanism; and to provide an apparatus of this kind which is simple and comparatively inexpensive in construction, easy and economical in operation and highly efficient in production.

An illustrative embodiment of this invention is shown in the accompanying drawings in which the figure represents diagrammatically a sublimating apparatus constructed in accordance with this invention.

An apparatus embodying this invention involved the use of a cylindrical member wherein is arranged a heating element with which the crude material entering at one end of the member is brought into intimate contact as it is caused to travel toward the opposite end of said member from which the remaining waste product is extracted, the vapors in the meantime being subject to the action of a hot-air current entering at said opposite end of said member and absorbing the vapors and forcing them out through said one end into a suitable chamber wherein the vapors are chilled so that the desired product solidifies and falls to the bottom of the chamber from whence it is discharged into the usual receptacles. The invention is

particularly designed for sublimating naphthalene although it is equally suitable for use in sublimating other sublimable substances such as benzoic acid, phthalic acid, etc.

In the illustrative embodiment herein shown, the apparatus comprises a vaporizing mechanism 1, a solidifying chamber 2 and a waste-products extracting mechanism 3.

The vaporizing mechanism is a long cylindrical member made up of a plurality of pipes 4 and a drum 5 rigidly secured together in axial alinement and rotatably supported in a nearly horizontal position on bearings 6, 7 and 8. These bearings are mounted on pillars or walls so as to locate the mechanism a certain distance above the floor and are relatively arranged so that the member is slightly inclined to the horizontal whereby the liquid crude material entering at the right hand end will gradually flow therealong toward the drum 5. Associated with the bearings 6, 7 and 8 are suitable means, herein shown in the form of jack screws 9 and 10 for the bearings 6 and 7, for use in altering the inclination of the pipes 4 and drum 5 whereby to regulate the velocity of the flow of the liquid through the vaporizing mechanism. The jack screws for the bearings 8 (which, jack screws are not shown) are arranged horizontally so as to move the rollers of each set of bearings horizontally toward and away from each other and thereby altering the position of the drum to conform with the inclination of the pipes 4.

A head 11 is arranged on the right hand end of the pipe 4 and provides support for the stuffing box 12 to which the steam and crude material inlets are connected. Suitable apertures are formed in the head 11 to permit the escape of vapors from the pipe 4 into the solidifying chamber 2.

The drum 5 being of much larger diameter than the pipe 4 locates the bottom of the drum so much lower than the bottom of the pipe that the drum provides a pit for the waste material to flow into from which it is extracted by mechanism hereinafter described.

A heating element 13 in the form of a steam coil is arranged within the pipes 4 in close proximity to the inner peripheries thereof. As herein shown this coil is spiral

- although it may consist of lateral runs of pipe. It connects with a steam supply pipe 14 which forms a steam jacket for the crude material inlet pipe 15 leading from the supply tank 16. These pipes are connected to the stuffing box 12 through which they extend to the interior of the pipe 4. The other end of the coil connects with a pipe 17 which forms a steam jacket for the waste-products outlet pipe 18, and from the lowest point in said steam jacket a pipe leads to a steam trap 19. These pipes 17 and 18 extend through a stuffing box 20 in the end of the drum 5.

15 Through the medium of the nozzles 21 a hot-air blast is injected into the vaporizing mechanism so as to absorb the vapors and cause a movement thereof along the pipes 4, counter to the movement of the incoming crude material, and out through the vapor outlet openings in the head 11 into the condensing chamber 2. These nozzles are rotatably connected to a header 22 which leads to a suitable source of heated air under pressure. At intervals along the pipes 4, baffles 23 may be arranged for the purpose of retarding the flow of air through said pipes and deflecting it outwardly against the periphery of the chamber.

20 A heat-resisting covering 24 of asbestos or other material surrounds the pipes 4 so as to retard as much as possible the dissipation of heat generated in the vaporizing mechanism 1.

25 The solidifying chamber 2 is located at the end of the vaporizing mechanism so as to receive the vapors as discharged through apertures in the head 11. This chamber is suitably chilled either by means of a denser 2^a or a cold-air blast (the latter of which is not herein shown) in order to cause a solidifying and consequent precipitation of the sublimate. This chamber is provided with an outlet 25 through which the sublimate may be discharged and conveyed to the usual receptacles in which it is to be stored or shipped. A flexible partition 38 extends from the head 11 to the surrounding wall of the chamber 2 so as to completely cut off any communication of the chamber with the exterior thereof.

30 The driving mechanism for rotating the vaporizing mechanism comprises a sprocket 26 arranged on the drum 5 and connected by a chain 27 to a smaller sprocket 28 mounted on a shaft 29. The shaft 29 is connected with a suitable source of power.

35 The waste-material extracting mechanism 3 comprises the pipe 18 enclosed in the steam jacket pipe 17 extending into the drum 5 through the stuffing box 20 and having the end 30 thereof disposed axially and opening close to the bottom of the left hand end of the drum 5. The pipe 18 is connected to receiving cylinders 31 which in turn are connected to a pipe 32 leading to a vacuum pump. Three-way valves 33 and 34 are arranged between the pipe 18 and the cylinders 31 and between the cylinders 31 and the pipe 32 respectively, whereby one at a time the cylinders 31 may be connected in between the vacuum pump and the pipe 18. The cylinders 31 are each equipped with a gauge 35, which enables the operator to observe the quantity of material therein, and with an air vent 36 which may be opened when it is desired to drain the respective cylinder through the valve controlled outlets 37.

40 The foregoing apparatus is supplemented by suitable alkali and acid washing mechanism similar to that which is now used for preparing the crude product for sublimation in the flame heated retorts by which sublimation has heretofore been carried on.

45 The operation of the device herein shown and described is substantially as follows: The washed crude material is delivered to the supply tank 16 in any convenient manner from which it is conveyed through the pipe 14 to the right hand end of the vaporizing mechanism 1. A valve 39 may be used to control the flow of crude material. Live steam admitted to the steam jacket 14 from the pipe 40 keeps the crude material passing through the pipe 15 in a liquid state and passing through the coil 13 provides the necessary heat for vaporizing the crude product passing through the pipes 4. As the steam flows from the coil 13 to the steam jacket pipe 17 it keeps the waste products flowing out through the pipe 18 in a liquid state.

50 The pipes 4 and drum 5 are gradually rotated so that as the liquid flows along the inclined pipes 4 it is also caused to travel up around the periphery and drop off onto the steam coil 13. The heat vaporizes the desired chemical which is absorbed by the heated air entering through the nozzles 21 and is caused to flow out through the apertures in the head 11 into the solidifying chamber 2. Here the vapors come in contact with the chilled air resulting in a solidification and precipitation of the sublimate which may be discharged through the opening 25 into receptacles.

55 The three-way valves 33 and 34 are set so that one at a time the receiving cylinders 31 are placed in circuit with the vacuum pump. This causes the waste products accumulating in the bottom of the drum 5 to be sucked in through pipe 18 and into the corresponding receiver 31. By means of the gauge 35 the operator can observe when the receiver is nearly full of waste product whereupon the valves 33 and 34 are shifted so as to place the other receiver 31 in circuit with the pump. Thereupon the vent 36 is opened and the contents of the receiver allowed to drain out through the valve controlled outlet 37.

60 If the products being sublimated require

more or less rapid flow through the pipes 4 the inclination thereof is adjusted accordingly by actuating the jack screws 9 and 10 and the jack screws (not shown) arranged in 5 conjunction with the bearings 8.

Although but one specific embodiment of this invention has been herein shown and described, it will be understood that numerous details of the construction shown may be 10 altered or omitted without departing from the spirit of this invention as defined by the following claims.

I claim:

1. An apparatus of the class described comprising a long cylindrical member providing a vaporizing chamber disposed substantially horizontal, a heating element arranged within said chamber and extending lengthwise thereof, a crude-material inlet arranged adjacent one end of said member, vapor outlet also arranged in said member adjacent one end thereof, means for causing the crude material to travel axially along said member and around the periphery thereof toward said other end, in close proximity to said heating element, and means for separately extracting the vapors and the waste products from said member.

2. An apparatus of the class described, the combination of a long cylindrical member providing a vaporizing chamber disposed in a horizontally inclined position, bearings supporting said member whereby it may be rotated, a crude-material inlet arranged adjacent one end of said member, a vapor outlet arranged in said member adjacent one end thereof, a heating element arranged within said chamber and extending lengthwise thereof, means for rotating said member so as to cause said crude material to move axially along said member and around the periphery thereof, and means for extracting the vapors from one end and the waste products from the opposite end of 45 said member.

3. An apparatus of the class described, the combination of a long cylindrical member providing a vaporizing chamber disposed in a horizontally inclined position, bearings supporting said member whereby it may be rotated, a crude-material inlet arranged adjacent one end of said member, a vapor outlet arranged in said member adjacent one end thereof, a heating element arranged 50 within said chamber and extending lengthwise thereof, means for rotating said member so as to cause said crude material to move axially along said member and around the periphery thereof, means for extracting the vapors from one end and the waste products from the opposite end of said member, and means for varying the inclination of 55 said member.

4. An apparatus of the class described, the combination of a long cylindrical member

providing a vaporizing chamber disposed in a horizontally inclined position, bearings supporting said member whereby it may be rotated, a crude-material inlet arranged adjacent one end of said member, a vapor outlet also arranged in said member adjacent one end thereof, a steam coil arranged in said chamber in close proximity to the periphery thereof, means for rotating said member so as to cause said crude material to move axially along said member and around the periphery thereof, and means for extracting the vapors from one end and the waste products from the opposite end of 70 said member.

5. An apparatus of the class described comprising a long cylindrical member providing a vaporizing chamber disposed substantially horizontal, a heating element arranged within said chamber and extending lengthwise thereof, a crude-material inlet arranged adjacent one end of said member, a vapor outlet also arranged in said member adjacent one end thereof, means for causing the crude material to travel axially along said 80 member and around the periphery thereof toward said other end in close proximity to said heating element, said member being shaped at the opposite end thereof so that the bottom of the chamber in said end is below the bottom 85 of the chamber in the remaining part of said member thereby providing a pit for receiving the waste products, a suction pipe extending into said opposite end of said member and having the end thereof located 90 near the bottom of said chamber, said pipe being adapted to be connected to a suction pump, and means for extracting the vapors from said chamber.

6. An apparatus of the class described, the combination of a long cylindrical member providing a vaporizing chamber disposed in a horizontally inclined position, bearings supporting said member whereby it may be rotated, a crude-material inlet arranged adjacent one end of said member, a vapor outlet also arranged in said member adjacent one end thereof, a heating element arranged within said chamber and extending lengthwise thereof, means for rotating said member so as to cause said crude material to move axially along said member and around the periphery thereof, a drum connected to the other end of said cylindrical member and forming a continuation thereof 105 and being rotatable therewith, a suction pipe extending into said drum axially thereof and having a radially disposed end with the opening therein located adjacent to the bottom of the chamber in said drum, said pipe 110 being adapted to be connected to a suction pump, and means for extracting the vapors from said chamber.

7. An apparatus of the class described comprising a member providing a vaporiz- 130

ing chamber, a heating element arranged within said chamber, a crude material inlet arranged adjacent one end of said member, a vapor outlet also arranged adjacent one 5 end thereof, means for causing the crude material to travel along said heating element, means for separately extracting the vapors and the waste products from said chamber, a chamber communicating with 10 said vapor outlet, and means for chilling said chamber to cause the solidifying of vapors discharged from said member.

8. An apparatus of the class described, the combination of a long cylindrical member 15 providing a vaporizing chamber disposed in a horizontally inclined position, bearings supporting said member whereby it may be rotated, a crude-material inlet arranged adjacent one end of said member, a 20 vapor outlet arranged in said member adjacent one end thereof, a hot-air blast inlet arranged adjacent the end of said member opposite the end in which said vapor outlet is located and arranged to force vapors out 25 through said vapor outlet, a heating element arranged within said chamber and extending lengthwise thereof, means for rotating

said member so as to cause said crude material to move axially along said member and around the periphery thereof, and 30 means for extracting the waste products from the opposite end of said member.

9. An apparatus of the class described, the combination of a long cylindrical member 35 providing a vaporizing chamber disposed in a horizontally inclined position, bearings supporting said member whereby it may be rotated, a crude-material inlet arranged adjacent one end of said member, a vapor outlet also arranged in said member 40 adjacent said one end thereof, a steam coil arranged in said chamber in close proximity to the periphery thereof, a hot-air blast inlet arranged adjacent to the other end of said member and arranged to force 45 vapors out through said vapor outlet, means for rotating said member so as to cause said crude material to move axially along said member and around the periphery thereof, and means for extracting the waste products 50 from the opposite end of said member.

Signed at Sandusky, Ohio, this second day of November, 1921.

ROBERT M. COLE.
